TRAY FOR A GOLF CART OR THE LIKE

Marvin R. Exline, 1356 E. 13th St., Des Moines, Iowa

Filed Apr. 11, 1960, Ser. No. 60,134

Term of patent 3½ years

(Cl. D34—5)

Fig. 1

Fig. 2

Fig. 3

Fig. 4

Fig. 6

Fig. 5

FIG. 1 is a top perspective view of a tray for a golf cart or the like showing my new design;

FIG. 2 is a side elevational view thereof;

FIG. 3 is a rear elevational view thereof;

FIG. 4 is a side elevational view showing the side opposite that shown in FIG. 2;

FIG. 5 is a front elevational view thereof; and

FIG. 6 is a bottom plan view thereof.

I claim:

The ornamental design for a tray for a golf cart or the like, substantially as shown.
